UNITED STATES PATENT OFFICE.

THEODORE H. PROSKE AND ALEXANDER L. PROSKE, OF DENVER, COLORADO.

DRILL-SHARPENER.

1,259,045.

Specification of Letters Patent. Patented Mar. 12, 1918.

Application filed December 23, 1916. Serial No. 138,672.

To all whom it may concern:

Be it known that we, THEODORE H. PROSKE and ALEXANDER L. PROSKE, citizens of the United States, residing at the city and county of Denver and State of Colorado, have invented certain new and useful Improvements in Drill-Sharpener; and we do declare the following to be a full, clear, and exact description of the invention, such as will enable others skilled in the art to which it appertains to make and use the same, reference being had to the accompanying drawings, and to the characters of reference marked thereon, which form a part of this specification.

Our invention relates to improvements in drill sharpening apparatus of the class in which the drill steel is clamped in place and acted on by a dolly which in turn is actuated by a reciprocating hammer. Our object is to provide an apparatus of this class which shall be comparatively simple in construction, economical in cost, reliable, durable and efficient in use and which shall require practically no skill on the part of the operator, since the device is to a great extent automatic in operation.

In our improvement one of the novel features consists in the construction whereby the drill steel is clamped or secured in place preparatory to the sharpening operation. This construction consists of a piston-operated rack toothed on its opposite edges and engaging two gears respectively mounted and made fast on shafts which are equipped with eccentric disks which engage openings formed in blocks which are equipped to engage the drill steel in clamping relation. As the said rack is moved in one direction the blocks are actuated to clamp the drill steel, while when it is moved in the opposite direction the blocks are actuated to release the drill steel. When the blocks are in the released or open position, the drill steel may be laid in place between them and properly adjusted, after which it is securely clamped in place. As soon as this happens the actuating fluid as air, is allowed to pass from the chest which it originally enters, to the valve mechanism of a reciprocable hammer mounted in a cylinder and connected to act upon the dolly for upsetting and sharpening the point or head of the drill steel.

Having briefly outlined our improved construction, we will proceed to describe the

same in detail, reference being made to the accompanying drawing, in which is illustrated an embodiment thereof.

In this drawing:—

Fig. 1 is a side elevation of our improved machine.

Fig. 2 is a top plan view of the same.

Fig. 3 is a horizontal section taken on the line 3—3, Fig. 1, looking downwardly.

Fig. 4 is a fragmentary view of the same shown on a larger scale.

Fig. 5 is the same as Fig. 4 but with the operating parts in different relative positions.

Fig. 6 is a top view of the clamping blocks shown partly in section, taken on the line 6—6, Fig. 7.

Fig. 7 is a view looking in the direction of arrow 7, Fig. 6, being a face view of the clamping blocks showing the drill steel in place. In Fig. 6, however, the full lines indicate the open position of the clamping or die blocks, while in Fig. 7 these blocks are shown in the closed position.

Fig. 8 is a horizontal section taken on the line 8—8, Fig. 1, the parts being shown on a larger scale.

The same reference characters indicate the same parts in all the views.

Let the numeral 5 designate a chest which receives motive fluid as air at one extremity through a supply pipe 6. This chest is secured to the side 7 of a cylinder 8 in which is located an operating piston 9. The cylinder is reinforced on the side 7 where the chest is secured and in this reinforcement are formed passages 10 and 12 which open at one extremity into the chamber 13 of the chest. The reinforced side 7 of the cylinder is also provided with an exhaust port or passage 14 which is arranged between the two passages 10 and 12. In the chamber of the chest 5 is arranged a slide valve 15 composed of two parts 16 and 17. The part 17 is angle-shaped, one of its parts 18 having a perforation 19 through which the stem 20 of a piston 21 passes, the slide valve member being secured to the rod by nuts 22 and 23 threaded on the stem and engaging the part 18 of the slide valve member in opposing relation. One extremity of the slide valve member 16 engages the nut 23 opposite the part 18 of the member 17, while the opposite extremity of the member 16 is acted on by a spiral spring 24 which surrounds the stem and is

arranged between the valve member 16 and a stop 25 on the stem. Hence, the member 16 is normally yieldingly retained in engagement with the nut 23, whereby the normal position of the two members 16 and 17 of the slide valve, is such that they both engage the nut 23. By virtue of this construction the slide valve member 17 is secured against movement on the stem, while the member 16 is free to slide thereon when sufficient resistance is offered to compress the spring 24. The movement of the member 16 is limited by offsets 26 and 27 formed on the adjacent face of the reinforced part 7 of the cylinder 8. It may be assumed that the normal position of the slide valve is that indicated in Fig. 4 in which the member 16 is in engagement with the offset 26. When in this position the passage 12 of the cylinder is in communication with a recess 28 of the slide valve member 16, this recess being also in communication with the exhaust passage 14 of the cylinder. Furthermore, when the slide valve is in the normal position or that shown in Fig. 4, the passage 10 of the cylinder is in communication with the chamber 13 of the chest, whereby when the motive fluid enters the chest through the supply pipe 6, it first fills the chest and flows thence by way of the passage 10 into the cylinder 8 and acts on the piston 9 to move the same rearwardly or toward the left in the event that the piston is not already at its rearward limit of movement. The piston 9 is secured to one extremity of a stem 29 which passes through a stuffing box 30 mounted on one end of the cylinder, its outer extremity being connected as shown at 31 with a rack bar 32 toothed or cogged on its opposite edges as shown at 33 to engage gears 34 and 35 which are respectively secured to shafts 36 and 37 which are equipped with eccentric parts or cams 38 and 39 which fit closely in openings 40 and 41 formed in blocks 42 and 43 which are equipped with dies 44 and 45 arranged to clamp the drill steel 46. These dies for the greater part of their length, are slightly concaved as shown at 47 and 48 to fit the cylindrical portion of the drill steel. However, from a point 49 (see Fig. 6) the recesses of these dies are enlarged, gradually increasing to their forward extremities so that when the dies are closed (see Fig. 7) these enlarged recesses or cone-shaped parts 50 and 51, directly engage the head 52 of the drill steel upon which the dolly 53 acts for sharpening purposes. This dolly is equipped with a stem 54 which enters a cylinder 55 in which is located a reciprocable hammer (not shown). This hammer cylinder is equipped with valve mechanism 56 which receives motive fluid through a pipe or conduit 57 whose extremity remote from the hammer cylin-

der, is in communication with the chest 5 by way of a port 58.

The chamber 13 of the chest 5 has an opening 59 at its bottom which is in communication with one extremity of a pipe 60 whose opposite extremity is in communication with a port 71 of a valve casing 72 which is also provided with three other ports designated 73, 74 and 75 respectively, the latter being an exhaust port (see Fig. 8). 75 Leading from the casing 72 and in communication with the port 73 thereof, is a pipe 76 which communicates with a port 77 of a small cylinder 62. Another pipe 78 communicates with the port 74 of the casing 72 at 80 one extremity while its opposite extremity communicates with a port 61 formed in the bottom of the cylinder 62 in which is fitted the piston 21 secured to the valve stem 20 as heretofore explained. The stem 20 passes 85 through a stuffing box 63 with which one extremity of the chest 5 is equipped. The opposite extremity of this cylinder is closed by a screw plug 64. Normally a valve 66 is adjusted in the casing 72 to allow the air 90 under pressure or other motive fluid in the chamber 13, to pass by way of the pipes 60 and 76, into a compartment 79 at the right of the piston 21 of the cylinder 62, a compartment 80 of the said cylinder on the opposite side of said piston being in communication with the atmosphere by way of the pipe 78, the valve chamber 86 and the exhaust port 75 of the casing 72. Hence the piston 21 is normally held at its limit of 100 movement toward the left whereby the slide valve is in engagement with the offset 26. However, as soon as the fluid has entered the chest 5 in sufficient volume to actuate the piston 9 and move it rearwardly or to 105 the position shown in Fig. 4, the valve 66 is manually operated to cut off the fluid from the compartment 79 of the cylinder 62 and cause it to enter this cylinder in the rear of the piston 21, while the port 75 of the casing 110 72 is placed in communication with a compartment 80 by way of the pipe 78 whereby the slide valve member 16 is moved from the offset 26 to the offset 27. As soon as this occurs the motive fluid in the chest is 115 allowed to flow (see Fig. 5) through the passage 12 into the cylinder 8 in the rear of the piston 9 upon which it acts to drive the said piston forwardly or to the position shown in Fig. 5, whereby the die blocks are actuated 120 to clamp the drill steel as heretofore explained. During this movement of the piston 9, the slide valve member 17 remains in its normal position with reference to the member 16. This normal position of the 125 member 17 is shown in full lines in Fig. 4 and in dotted lines in Fig. 5. During the movement of the piston 9 from the position shown in Fig. 4 to that shown in Fig. 5, the piston 21 remains in the dotted line po- 130

sition in Fig. 5, since the pressure is reduced slightly in the cylinder 62 while the fluid is flowing from the valve chest into the cylinder 8. However, as the area of the piston 9 acted on by the fluid, is relatively large, the piston 9 is actuated to operate the rack bar 32 and actuate the die blocks to securely clamp the drill steel. After this occurs the pressure increases in the compartment 80 of the cylinder 62 and acts upon the piston 21 to move the latter from the dotted line position in Fig. 5 to the full line position in the same figure, and during this movement of the piston 21 the slide valve member 17 is moved independently of the member 16, a sufficient distance to uncover the port 58 and allow the motive fluid to pass from the chest 5 through the pipe 57, to the valve mechanism 56 of the hammer cylinder 55. As soon as this occurs the motive fluid serves to impart the usual reciprocating movement to the hammer, whereby the dolly 53 is acted on to upset and sharpen the point or head of the drill steel. Attention is called to the fact that the dolly 53 is exposed to the view of the operator or person in charge so that he may observe its action upon the drill steel, and whereby he may know when the dolly has properly performed its function. The dolly is provided with a shoulder 67 which will engage faces 68 of the die blocks when the dolly is at its forward limit of movement. If it should then happen that the drill steel is not fully upset or sharpened, the motive fluid may be cut off from the hammer cylinder, the die blocks opened through the medium of the piston 9, and the drill steel moved toward the left (see Fig. 6). In this event the dolly will be moved in a corresponding direction, since the fluid pressure is cut off from the hammer cylinder. As soon as the drill steel is properly adjusted, the die blocks will be actuated in the manner heretofore explained to clamp the drill steel tightly in place, after which the hammer will be operated to actuate the dolly until the drill-sharpening operation is completed.

From the foregoing description the use and operation of our improvement will be readily understood. It should be explained that the construction may be employed for upsetting and shaping metal bars of any description whether of the drill steel or any other construction. We term the machine a drill sharpening apparatus because the use which we particularly have in mind, is the upsetting of the heads or operating points or extremities of drill steels for shaping and sharpening purposes, though it must be understood that the invention is not limited to this particular use.

In describing the operation it should be assumed that the chest 5 is open through the pipe 6 to a source of motive fluid supply.

Assuming that the piston 9 is at its forward limit of movement or at its limit of movement toward the right in the cylinder 8, and assuming also that the slide valve is in its normal position (see Fig. 4), the motive fluid will first flow through the passage 10 into the cylinder 8 and act on the piston 9 to move the latter rearwardly or to the position shown in Fig. 4. We will also assume that the valve 66 is in the position shown in full lines in Fig. 8, while the compartment 79 of the cylinder 62 is under fluid pressure to maintain the piston 21 at its limit of movement toward the left. The valve 66 will then be given quarter turn or moved to the position indicated by dotted lines in Fig. 8, whereby the motive fluid is cut off from the compartment 79 of the cylinder 62 and allowed to enter the compartment 80, the compartment 79 being placed in communication with the atmosphere. The motive fluid will then act on the piston 21 to move the latter forwardly or toward the right in the cylinder 62 whereby the member 16 of the slide valve is placed in the position shown in Fig. 5 and the extremity of the passage 12 in communication with the fluid chest is uncovered and the corresponding extremity of the passage 10 opened to the exhaust. The motive fluid will then flow through the passage 12 into the cylinder 8 in the rear of the piston 9 and act on the latter to drive it forwardly, whereby the rack bar 32 will be actuated to operate the gears 34 and 35 sufficiently to actuate the jaws, clamping blocks or die blocks 42 and 43 through the medium of the eccentric cams 38 and 39, whereby the drill steel 46 will be securely clamped in place, the drill steel having been placed manually in position between the jaws when the latter were open. During this operation of the piston 9 and its connections for clamping the drill steel in place, the piston 21 has remained stationary, due to the reduction of pressure in the chest 5 due to the passage of motive fluid from the chest into the cylinder 8. However, as soon as the piston 9 is moved to actuate the jaws or clamping blocks as just explained, the pressure will accumulate in the chest 5 and act through the pipe 60, the casing 72 and the pipe 78 to drive the piston 21 forwardly in the cylinder 62, this movement being sufficient to actuate the slide valve member 17 (see Fig. 5) and uncover the port 58 whereby the motive fluid is allowed to flow through the pipe 57 to the hammer cylinder 55 where it acts to reciprocate the hammer or piston (not shown) in the cylinder, the said hammer acting on the stem 54 of the dolly 53 to cause the latter to upset the head or point of the drill steel.

It will thus be noted that from the time the valve 66 is moved to the dotted line position in Fig. 8, the action of the piston

21 in manipulating the slide valve 16 for the purpose of controlling the supply of motive fluid to the cylinders 8 and 55, is entirely automatic, notwithstanding the fact 5 that there must be a cessation of movement on the part of the slide valve member 17 after the passage 12 is opened to the valve chest, and until the piston 9 is actuated sufficiently to cause the clamping blocks or 10 jaws to grasp the drill steel or other bar which it may be desired to hold in place for upsetting purposes.

Having described our invention what we claim is:

15 1. A drill sharpener including a pair of eccentrically mounted clamping blocks adapted to hold a drill steel, a dolly positioned to act on the drill steel when held by the blocks, a fluid actuated hammer for operating the dolly, a piston, means for connecting said piston in operative relation with the clamping blocks including a rack bar and coöperating gears, and means for automatically controlling the supply of motive 20 fluid to the said hammer and piston.

25 2. A drill sharpener including a pair of eccentrically mounted clamping jaws adapted to hold a drill steel, a dolly positioned to act on the drill steel when held by the jaws, a fluid actuated hammer for operating the dolly, a piston, means for connecting the piston in operative relation with the clamping jaws including a rack bar and coöperating gears, means for automatically controlling 30 the supply of motive fluid to the hammer and piston, said means comprising a valve chest in communication with a supply of motive fluid and also in communication with said hammer and piston, a valve 35 in the chest and means for actuating the valve.

40 3. A device of the class described including a pair of eccentrically mounted clamping jaws adapted to hold a bar, a dolly positioned to act on the bar when held by the jaws, a fluid actuated hammer for operating the dolly, a piston, means for connecting the piston in operative relation with the clamping jaws including a double rack bar and coöperating gears, means for automatically controlling 45 the supply of motive fluid to the hammer and piston to cause the piston to act in advance of the hammer, said means comprising a chest in communication with a supply of motive fluid and also in communication with said hammer and piston, a valve 50 in the chest, and means operated by fluid taken from the chest for automatically actuating the valve.

55 4. A device of the class described including a pair of clamping jaws adapted to hold a bar, a dolly positioned to act on the bar when held by the jaws, a fluid actuated hammer for operating the dolly, a piston 60 connected in operative relation with the

clamping jaws, means for automatically controlling the supply of motive fluid to the hammer and piston to cause the piston to act in advance of the hammer, said means comprising a chest in communication with a supply of motive fluid and also in communication with said hammer and piston, a valve movable in the chest for controlling the passage of the motive fluid, and means operated by fluid taken from the chest to automatically operate the said valve.

5. A device of the class described, including a pair of eccentrically mounted clamping jaws adapted to hold a bar, a dolly positioned to act on the bar when held by the jaws, a fluid actuated hammer for operating the dolly, a piston connected in operative relation with said jaws to oscillate the same, and means for controlling the supply of motive fluid to the hammer and piston.

6. A device of the class described, including a pair of clamping jaws adapted to hold a bar, a dolly positioned to act on the bar when held by the jaws for upsetting purposes, a fluid-actuated hammer for operating the dolly, a piston connected in operative relation with the jaws, means for automatically controlling the supply of motive fluid to the hammer and piston, said means comprising a chest in communication with a supply of motive fluid and also in communication with said hammer and piston, a valve movable in the chest for controlling the passage of motive fluid, means operated by fluid taken from the chest to operate said valve, said means including a cylinder and a piston therein, a stem on which the last named piston is mounted, and an operative connection between said stem and said valve.

7. A device of the class described, including a pair of clamping jaws adapted to hold a bar, a dolly positioned to act on the bar when held by the jaws for upsetting purposes, a fluid-actuated hammer for operating the dolly, a piston connected in operative relation with the jaws, means for automatically controlling the supply of motive fluid to the hammer and piston, said means comprising a chest in communication with said hammer and piston, a valve movable in the chest for controlling the passage of the motive fluid, means operated by fluid taken from the chest to operate said valve, said means including a cylinder, a piston therein, a stem on which the last named piston is mounted and which also carries the said valve, and means for releasing the fluid pressure on one side of the last named piston and switching it to the opposite side for reversing the said piston's movement.

8. A machine of the class described, including a pair of clamping jaws adapted to hold a bar, an upsetting device positioned

to act on the bar when held by the jaws, a fluid-actuated hammer for operating the upsetting device, a piston connected in operative relation with the jaws, a chest in communication with a supply of motive fluid and also in communication with the said hammer and piston, a valve movable in the chest for controlling the supply of motive fluid, a second piston, means for conducting motive fluid from the chest to the second piston, and a stem on which said valve and second piston are mounted.

9. A machine of the class described, including a pair of clamping jaws adapted to hold a bar, an upsetting device positioned to act on the bar when held by the jaws, a motive-fluid-actuated hammer for operating the upsetting device, a piston connected in operative relation with the jaws, a chest in communication with a supply of motive fluid and also in communication with the said hammer and piston, a valve movable in the chest for controlling the supply of motive fluid, a second piston, a conduit leading from the chest to the second piston, a manually operable valve in said conduit, and a stem on which said chest valve and second piston are both mounted.

10. A machine of the class described, including a pair of clamping jaws adapted to hold a bar, an upsetting device positioned to act on the bar when held by the jaws, a fluid-actuated hammer for operating the upsetting device, a cylinder, a piston therein, a rack bar connected with the piston, gears engaged by the rack bar, shafts on which the gears are made fast, eccentrics carried by the shafts and fitting openings formed in the respective jaws, and means for automatically controlling the supply of motive fluid to the hammer and piston.

11. A machine of the class described, in-

cluding a pair of clamping jaws adapted to hold a bar, an upsetting device positioned to act on the bar when held by the jaws, a fluid-actuated hammer for operating the upsetting device, a cylinder, a piston mounted to reciprocate therein, a rack bar carried by the piston, gears engaged by the rack bar, shafts upon which the gears are mounted, cam members carried by the respective shafts, the said jaws having openings in which the cam member portions of the said shafts are fitted, and means for automatically controlling the supply of motive fluid to the hammer and piston to cause the piston to act in advance of the hammer.

12. A machine of the class described, including a pair of eccentrically operated clamping jaws adapted to hold a bar, an upsetting device positioned to act on the bar when held by the jaws, a motive fluid actuated hammer for operating the upsetting device, a cylinder, a piston mounted to reciprocate therein, a rack bar connected in operative relation with the piston, gears meshing with said bar, shafts on which the gears are mounted and made fast, the shafts being respectively equipped with eccentrics or cam members, the said jaws having openings in which the eccentric or cam member portions of the two shafts are respectively fitted, a chest in communication with a supply of motive fluid and also in communication with said hammer and piston, a valve in a chest, a stem on which the valve is mounted, and means for operating the valve.

In testimony whereof we affix our signatures, in presence of two witnesses.
